CLOTHES WRINGER

George W. Dunham, Westport, Conn., assignor to
General Electric Company, a corporation of
New York

Application July 5, 1935, Serial No. 29,824

11 Claims. (Cl. 68—32)

The present invention relates to clothes wringers of the type suitable for use with washing machines and the like.

The object of my invention is to provide an improved construction and arrangement in a clothes wringer in which the drainboards may be used to enclose the wringer when not in use.

For a consideration of what I believe to be novel and my invention, attention is directed to the accompanying description and the claims appended thereto.

In the accompanying drawing, Fig. 1 is a perspective view of a clothes wringer embodying my invention showing the drainboards in the lowered position; Fig. 2 is a front elevation partly in section of one end of the wringer showing the wringer in the enclosed position; Fig. 3 is a sectional end elevation taken along line 3—3 of Fig. 2; Fig. 4 is a sectional view taken on line 4—4 of Fig. 3 showing the arrangement for pivoting the drainboards; Fig. 5 is a sectional view taken on line 5—5 of Fig. 2; Fig. 6 is a sectional view taken on line 6—6 of Fig. 2; and Fig. 7 is a fragmentary view showing the manner of supporting the roll guard.

Referring to the drawing, the numeral 1 indicates the wringer frame having spaced side stiles 2 and 3 at either end thereof between which are rotatably carried a pair of cooperating wringer rolls 4. To the side stile 2 is secured a casing 5 which contains the driving mechanism for the wringer rolls and which is provided with a depending sleeve 6 adapted to fit over the wringer post of a domestic washing machine to support the wringer. To the side stile 3 is fixed a cover plate 7. Extending between the side stiles and above the wringer rolls is a control bar 8 which, when pivoted to either side of the central position shown in Fig. 3, controls the direction of rotation of the wringer rolls and also controls the pressure between the rolls. When the control bar 8 is in its central position it may be lifted.

As shown in Fig. 7, the control bar 8 is fixed to shaft 28a on which the upper roll is rotatably carried. Pivoted on the shaft 28a is a roll guard 28 which overlaps the ends of the wringer rolls and prevents clothes from passing beyond the ends of the rolls. As shown in Figs. 1 and 3, the sides of the roll guards are indented to more closely conform to the rolls. This increases the effectiveness of the roll guard. In the lower end of the roll guard is an open-ended slot 30 which fits over the lower roll shaft 31 and maintains the roll guard centered with respect to the rolls.

The wringer described above is of the general type shown in Patent 1,906,407,—Perkins et al.

On either side of the wringer are provided drainboards 9 having up-turned side flanges 10 extending along each side thereof for preventing the flow of water over the sides of the drainboards. At the end of the side flanges 10 adjacent the wringer frame, the side flanges are provided with thickened cam shaped bosses 11 into which are threaded pivot pins 12. The pivot pins 10 fit within holes 13 in the side stiles and pivotally support the drainboards thereon, as shown in Fig. 4. The drainboards are held in the lowered position by braces 14 which are carried on the upper side of the drainboards by hinges 15. As shown in Fig. 1, these braces have projecting portions 16 which are adapted to fit within depressions 17 in the wringer frame. When the braces are swung to the position shown at the left-hand end of Fig. 1, the braces are held in this position by 20 spring pressed pins 18 mounted in the underside of the wringer frame which engage ears 19 on the drainboards. Fig. 5 is an enlarged sectional view of these pins. These spring pressed pins urge the drainboards toward the raised position and maintain the braces 14 under compression, thereby 25 maintaining the projections 16 of the braces seated within the depressions 17. The drainboards are therefore securely held in the lowered position. The depressions 17 are arranged so 30 that if the material passing between the rolls catches on the drainboards, the line of action of the force exerted on the drainboards will pass below the depressions 17 and the braces will therefore be securely held in place. As shown 35 in Fig. 1, the braces are inclined from the outer edge of the drainboard toward the center of the wringer and, in addition to holding the drainboards in the lowered position, provide guides for guiding the material toward the center of the 40 wringer rolls thereby preventing the material from moving beyond either end of the wringer rolls. This is important because material passing beyond either end of the wringer rolls will 45 not be properly wrung and may become soiled or damaged due to contact with the operating mechanism for the wringer rolls.

As shown at the right-hand end of Fig. 1, the braces 14 may be swung to a position in which they lie flat on the upper surface of the drainboards. When the braces are in this position, the drainboards may be pivoted on pins 12 to a position between the side stiles 2 and 3. In this position, the drainboards enclose the space 50 between the side stiles. In order to close the 55

space over the top of the rolls, plates 20 are provided which are hinged on the under or outer side of the drainboards. The hinges for supporting the plates 20 each comprise a bolt 21 which extends through a sleeve 22 formed integral with the plates 20 and through a boss 23 on the under side of the drainboard. Within the sleeve 22 and between the head of the bolt and the boss 23 is arranged a tubular sleeve 24 5 which is pressed against the head of the bolt by a compression spring 25. A ring of friction material 26 is arranged between the spring and the sleeve 24 and provides friction which prevents free swinging of the plates 20 on the drainboards. This friction is such that the plates will 10 tend to remain in a fixed position with respect to the drainboards. When the drainboards are in the raised position, the upper edges of plates 20 fit under ears 27 on the control bar 8 and thereby hold the drainboards in the raised position. When the drainboards are in the lowered position, the plates 20 may be swung to a position underneath the drainboards as shown in 15 Fig. 3 so that the plates will not interfere with the operation of the wringer. The drainboards when released to open are prevented from falling with a clatter by a U-shaped spring 28 which is fastened to the under side of the wringer frame 1 and which bears on the cam shaped bosses 11 20 which present an increasing radius as the drainboard opens.

In the use of the wringer the operating lever 8 is first lifted until the ears 27 are clear of the upper edges of plates 20. The drainboards 9 are 25 then swung downward to the lowered position, and the braces 14 are swung upward to the position in which the projections 16 of the braces fit within the depressions 17 of the wringer frame. During this movement, the spring 30 pressed pins 18 permit the drainboards to be moved downwardly so that the braces 14 may be swung into the raised position. When the braces are in the raised position, the spring 35 pressed pins 18 engage ears 19 and tend to force 40 the drainboards toward the raised position, thereby holding the braces under compression and maintaining the projections 16 within the 45 depressions 17. The plates 20 may now be swung to a position beneath the drainboards where 50 they will not interfere with the use of the wringer.

At the conclusion of the wringing, the drainboards may be returned to the position shown in Fig. 2 in which they enclose the wringer. In 55 this operation the outer end of the drainboards is pressed downward until the projections 16 of the braces are clear of the depressions 17. The braces 14 are then swung downward on the upper surface of the drainboards, and the drainboards 60 are raised to a position between the side stiles. The plates 20 are then swung to a position over the top of the wringer rolls, the control bar 8 is lifted, the edges of the plates 20 placed beneath ears 27, and the control bar is then 65 lowered, so that the ears 27 extend over the upper edge of plates 20 and hold the plates in place.

What I claim as new and desire to secure by Letters Patent in the United States is:

1. In a wringer, a frame having spaced side 70 stiles, drainboards carried by the frame, said drainboards being hingedly movable from a lowered position projecting from opposite sides of the frame to a raised position closing the space between the side stiles, means on the wringer 75 for holding the drainboards in the raised position,

and braces operatively located between the frame and the drainboards, said braces being movable to a position extending between the drainboards and the frame for holding the drainboards in the lowered position.

2. In a wringer, a frame having spaced side 10 stiles, drainboards carried by the frame, said drainboards being hingedly movable from a lowered position projecting from opposite sides of the frame to a raised position closing the space 15 between the side stiles, means on the wringer for holding the drainboards in the raised position, and braces hinged on the drainboards, said braces being movable to a position engaging the frame for holding the drainboards in the lowered position.

3. In a wringer, a frame having spaced side 20 stiles, drainboards pivoted on the frame, said drainboards being movable from a lowered position projecting from opposite sides of the frame 25 to a raised position closing the space between the side stiles, braces operatively located between the frame and the drainboards, said braces being movable to a position extending between the drainboards and the frame for holding the drainboards in the lowered position, and spring means acting on the drainboards for maintaining the braces under compression when the drainboards are in the lowered position.

4. In a wringer, a frame having spaced side 30 stiles, drainboards pivoted on the frame, said drainboards being movable from a lowered position projecting from opposite sides of the frame to a raised position closing the space between the side stiles, braces hinged on the drainboards, said braces being movable to a position in which portions of the braces rest in depressions in the frame for holding the drainboards in the lowered position, and spring means acting on the drainboards for holding the braces within said depressions when the drainboards are in the lowered position.

5. In a wringer, a frame, rolls carried by the frame, a drainboard projecting from one side of the frame, and a brace extending between the 45 upper side of the drainboard and the frame whereby an upward force on the drainboard will be transmitted through the brace to the frame, said brace being inclined from the outer edge of the drainboard toward the center of the wringer 50 and providing a guide for guiding material to the rolls.

6. In a wringer, a frame having spaced side 55 stiles, drainboards carried by the frame, said drainboards being hingedly movable from a lowered position projecting from opposite sides of the frame to a raised position closing the space between the side stiles, and plates pivotally carried on the drainboards for closing the space between the top of the drainboards when the drainboards are in the raised position.

7. In a wringer, a frame having spaced side 65 stiles, drainboards carried by the frame, said drainboards being hingedly movable from a lowered position projecting from opposite sides of the frame to a raised position closing the space between the side stiles, plates pivotally carried on the drainboards for closing the space between the top of the drainboards when the drainboards are in the raised position, a control bar extending across the top of the frame, and means on said control bar for engaging said plates to hold said drainboards in the raised position.

8. In a wringer, a frame having spaced side 70 stiles, drainboards pivoted on the frame, said 75

- drainboards being movable from a lowered position projecting from opposite sides of the frame to a raised position closing the space between the side stiles, braces carried by the wringer, said braces being movable to a position extending between the drainboards and the frame for holding the drainboards in the lowered position, ears on said drainboards, and spring means on the under side of said frame for engaging said ears and maintaining the braces under compression when the drainboards are in the lowered position.
9. In a wringer, a frame having spaced side stiles, drainboards pivoted on the frame, said drainboards being movable from a lowered position projecting from opposite sides of the frame to a raised position closing the space between the side stiles, braces carried by the wringer, said braces being movable to a position extending between the drainboards and the frame for holding the drainboards in the lowered position, ears on said drainboards, and spring pressed pins on the under side of said frame for engaging said ears and maintaining the braces under compression when the drainboards are in the lowered position.
10. In a wringer, a frame having spaced side stiles, a drainboard carried by the frame, said drainboard being hingedly movable from a lowered position projecting from the frame to a raised position closing the space between the side stiles, and a brace hinged on the upper surface of the drainboard and movable from a position on the face of the drainboard to a position extending between the drainboard and the frame.
11. In a wringer, a frame having spaced side stiles, drainboards carried by the frame, said drainboards being hingedly movable from a lowered position projecting from opposite sides of the frame to a raised position closing the space between the side stiles, and a plate carried on the under side of one of the drainboards for closing the space between the top of the drainboards when in the raised position, said plate being movable to a position underneath the drainboard when the drainboard is in the lowered position.

GEORGE W. DUNHAM.
